GARDEN HOSE HOLDER

Joe H. Friedman, Amarillo, Tex.

Application January 12, 1954, Serial No. 28,496

Term of patent 14 years

(Cl. D91—1)

FIG. 1.

FIG. 2.

To all whom it may concern:

Be it known that I, Joe H. Friedman, a citizen of the United States of America, residing at Amarillo, in the county of Potter and State of Texas, have invented a new, original, and ornamental Design for a Garden Hose Holder, of which the following is a specification, reference being had to the accompanying drawing, forming part thereof.

I claim:

The ornamental design for a garden hose holder, substantially as shown.
